(57) **CLAIM**

The ornamental design for a metal finishing rotary tool, as shown and described.

DESCRIPTION

FIG. 1 is a front perspective view of a metal finishing rotary tool showing my new design;

FIG. 2 is a front view thereof;

FIG. 3 is a rear view thereof;

FIG. 4 is a left side view thereof;

FIG. 5 is a right side view thereof;

FIG. 6 is a top view thereof; and,

FIG. 7 is a bottom view thereof.

The broken line showing of portions of the metal finishing rotary tool in FIGS. 1-7 is for the purpose of illustrating environmental structure and forms no part of the claimed design.

1 Claim, 6 Drawing Sheets

FIG. 2

FIG. 3

FIG. 4

FIG. 5

FIG. 6

FIG. 7
